US0D1015280S

(12) **United States Design Patent** (10) **Patent No.:** **US D1,015,280 S**
(45) **Date of Patent:** **** Feb. 20, 2024**

(54) **LOW-PROFILE CABLE ARMOR**

(71) Applicant: **AFC Cable Systems, Inc.**, New Bedford, MA (US)

(72) Inventors: **Peter Lafreniere**, Mattapoisett, MA (US); **Stephen Lundgren**, Marion, MA (US); **Paulo Damoura**, Dorchester, MA (US); **Ronald Pegg**, New Bedford, MA (US); **Antonio Araujo**, New Bedford, MA (US); **David Campbell**, Bristol, RI (US)

(73) Assignee: **AFC Cable Systems, Inc.**, New Bedford, MA (US)

(**) Term: **15 Years**

(21) Appl. No.: **29/882,225**

(22) Filed: **Jan. 12, 2023**

Related U.S. Application Data

(63) Continuation of application No. 29/811,296, filed on Oct. 13, 2021, now abandoned, which is a continuation of application No. 29/706,679, filed on Sep. 23, 2019, now Pat. No. Des. 935,731.

CLAIM

The ornamental design for a low-profile cable armor, as shown and described.

DESCRIPTION

FIG. 1 is an isometric view of our new design;

FIG. 2 is a first side view of the design of FIG. 1;

FIG. 3 is a second side view and of the design of FIG. 1;

FIG. 4 is a first end view of the design of FIG. 1;

FIG. 5 is a second end view of the design of FIG. 1.

FIG. 6 is a top view of the design of FIG. 1; and,

FIG. 7 is a bottom view of the design of FIG. 1.

The broken lines in the drawings depict portions of the low-profile cable armor that form no part of the claimed design.

1 Claim, 6 Drawing Sheets
